UNITED STATES PATENT OFFICE.

EDWARD JESCHKE, OF BELLEVUE, OHIO.

DITCHING-MACHINE.

1,174,986.

Specification of Letters Patent. Patented Mar. 14, 1916.

Application filed November 25, 1914. Serial No. 873,976.

To all whom it may concern:

Be it known that I, EDWARD JESCHKE, a citizen of the United States, residing at Bellevue, in the county of Huron and State of Ohio, have invented certain new and useful Improvements in Ditching-Machines, of which the following is a specification.

My invention relates to machines for digging ditches or trenches and has particular reference to improvements in such a machine, shown and described in Letters Patent of the United States No. 1,048,014, granted to Frederick J. Wertelewski, under date of December 24th, 1912.

An important object of the invention is to provide means for rendering more convenient the vertical adjustment of the frame of the machine.

A further object of the invention is to provide means for improving the steering of the machine during its longitudinal travel.

A further object of the invention is to provide novel and improved means for connecting the excavator with the frame, to strengthen the same.

A further object of the invention is to provide means which will remove the soil from proximity to both sides of the ditch or trench being dug, in a highly efficient manner.

A further object of the invention is to provide self-adjusting means for preventing the body portion of the machine from tilting laterally, during its longitudinal travel.

A further object of the invention is to provide an adjustable grading or leveling device, to be carried by the machine.

A further object of the invention is to improve the construction of the machine in general, with a view of rendering the same more efficient in operation, and convenient in use.

Other objects and advantages of the invention will be apparent during the course of the following description.

In the accompanying drawings forming a part of this specification and in which like numerals are employed to designate like parts throughout the same, Figure 1 is a side elevation of a machine embodying my invention, Fig. 2 is a plan view of the same, Fig. 3 is an enlarged fragmentary detail section taken on line 3—3 of Fig. 2, Fig. 4 is a transverse sectional view taken on line 4—4 of Fig. 2, parts being omitted, Fig. 5

is a transverse sectional view taken on line 5—5 of Fig. 1, Fig. 6 is a similar view taken on line 6—6 of Fig. 1, Fig. 7 is a transverse section taken on line 7—7 of Fig. 2, parts 60 being omitted, and, Fig. 8 is a similar view, taken on line 8—8 of Fig. 2.

In the drawings, wherein for the purpose of illustration is shown a preferred embodiment of my invention, the numeral 10 designates an inclined longitudinal beam extending downwardly toward its forward end. Connected with the forward end of the beam 10 is a guide-frame 11, having a rear beam receiving portion 12 formed U-shaped in 70 cross-section, as more clearly shown in Fig. 8. This portion 12 is rigidly connected to the beam 10 by means of bolts 13 or the like. The guide-frame 11 (see Fig. 5) has a vertical transverse opening 14, receiving a vertically movable or reciprocatory rack-bar 15, preferably formed square in cross-section, as shown in Fig. 2. This rack-bar is provided upon its rear side with gear-teeth 16 for a purpose to be explained. The rack-bar 15 is provided with an axially extending cylindrical opening 17 (see Fig. 5), receiving a vertical stub-shaft 18, to the lower end of which is rigidly attached a fork 19. This fork receives a forward supporting-wheel 80 20, rotatably connected therewith by means of an axle 21 or the like. Attached to the rear portion of the upper end of the fork 19 is a scraper 22, extending downwardly in proximity to the ground-wheel 20, to slidably engage the same and remove therefrom the dirt or the like accumulating thereon.

The numeral 23 designates a tongue, the rear end of which is rigidly connected with spaced strips 24, arranged upon opposite 95 sides of the fork 19 and pivoted therewith to be swung in a vertical plane, by means of bolts 25 or the like. Disposed above the tongue 23 is a clevis 26, rigidly secured to the forward end of the guide-frame 11, as 100 shown. The draft appliance, (not shown) is secured to the clevis 26 and the forward end of the tongue 23 is connected with the collars of the horses or draft animals by the usual means, there being preferably two 105 draft animals employed in operating the machine. It is thus seen that the forward supporting wheel 20 is free to be swung laterally during the travel thereof, thus making the steering of the machine easier.

The numeral 27, (see Figs. 1 and 3) designates a preferably metallic L-shaped

depending beam extension, rigidly secured to the rear end of the beam 10, the same embodying an upper socket 28 (see Fig. 4), formed U-shaped in cross-section, to receive 5 the rear end of the beam 10, the beam being held therein by means of a bolt 29 or the like, as shown. Rigidly connected with the horizontal arm of the L-shaped beam extension 27 is a fork 30, having a rear supporting-wheel 31, rotatable therein and connected therewith by an axle 32 or the like. A scraper 33 has its upper end attached to the upper end of the fork 30 and extends downwardly and rearwardly of the supporting-wheel 31 to slidably engage therewith to move the dirt and the like therefrom.

Connected with the horizontal arm of the L-shaped beam extension 27 is a suitably stiff seat-spring 34, to the upper end of 20 which is attached a seat 35, as shown.

In the Patent No. 1,048,014, is shown plow handles attached to the rear end of the frame of the machine, so that an operator could walk behind the machine and by 25 means of these handles prevent the body portion of the machine from tilting laterally in either direction. However, I have found that such means were not altogether satisfactory, it being often difficult for the 30 operator to prevent this lateral tilting, particularly if the machine is constructed of a good size, and when the draft animals pull suddenly or unevenly. Besides from this disadvantage, it is obvious that the presence 35 of an additional operator is required.

In the present improved construction, I have provided self-adjusting means for preventing the tilting of the body portion of the machine laterally, but allowing the same 40 to move vertically when desired. Such means comprise a crank-axle 36, arranged near and above the rear end of the longitudinal beam 10. This crank axle has its central portion journaled through a bearing 45 37, rigidly attached to the beam 10 by means of bolts 38 or the like. A sleeve 39 is rigidly secured to the crank axle and engages one end of the bearing 37, while a crank or arm 40 is rigidly secured to the crank-axle and 50 engages the opposite end of the bearing, thus preventing perceptible longitudinal movement of the crank-axle with relation to the bearing but allowing the same to freely turn. At its opposite ends, the crank-axle 36 carries depending cranks or extensions 41, provided with horizontal portions 42, having side balancing-wheels 43 rotatable thereon. Attached to the outer end 55 of the crank 40 is a suitably stiff retractile coil spring 44, the lower end of which is connected with a bracket 45, (see Fig. 3) attached to the upper end of the beam extension 27. The function of this spring and associated elements is to oppose the rearward swinging movement of the cranks 41

of the crank-axle 36, thus preventing the body portion of the machine from tilting laterally, but allowing of the vertical movement of the beam 10 and associated elements with respect to the wheels 43, whereby the 70 supporting-wheels 20 and 31 may travel in proper engagement with the bottom of the ditch being dug, which varies in depth according to the number of times that the machine is driven over or through the same 75 ditch, the wheels 43 traveling upon the upper surface of the ground at points spaced from the ditch. As considerable strain is placed upon the crank-axle, it is advantageous to provide diagonal braces 46, (see 80 Fig. 2) the rear ends of which are apertured to rotatably receive the crank-axle 36 and engage the rings 47 rigidly secured to the crank-axle and arranged inwardly of and adjacent the apertured ends of the diagonal braces 46. The forward ends of these diagonal braces are rigidly connected with the longitudinal beam 10 by means of a bolt 48 or the like.

Rigidly attached to the diagonal braces 90 46 are auxiliary diagonal braces 49, extending forwardly and passed through the apertured head 50 (see Figs. 1, 2 and 6) of an upstanding triangular bracket 51, which is rigidly mounted upon the beam 10, and attached thereto by bolts 52. The forward ends of the auxiliary brace rods 49 are screw-threaded for receiving nuts 53 or the like, as shown.

The means to raise and lower the rack-bar 15, comprises a pinion or gear 57 (see Figs. 1 and 2), carried by a shaft 58, journaled through upstanding portions of the guide-frame 11, as shown. Arranged exteriorly of the guide-frame and rigidly connected with the shaft 58 is a worm wheel 59, engaging a worm 60, carried by a longitudinally extending operating shaft 61. This operating shaft has its forward portion journaled through apertured ears or members 62, rigidly attached to the guide-frame by any suitable means. The rear portion of the operating shaft 61 is journaled through an apertured arm or bracket 62', the lower end of which is rigidly attached to the upper end of the beam extension 27, as shown. Rigidly connected with the rear end of the operating shaft 61 is a hand wheel 63, arranged in convenient reach of the operator upon the seat 35, as shown.

The numeral 64 designates an elongated substantially U-shaped cutter or excavator (see Fig. 6), the forward edge of which is suitably sharpened. The upper ends of the cutter 64 are arranged upon and engage the 125 opposite ends of a transverse tubular attaching-member 65, and are rigidly secured thereto by a transverse bolt 66, passing therethrough, as shown. Rigidly attached to the tubular member 64 is a socket 67, 130

formed U-shaped in cross-section, receiving the beam 10, and rigidly attached thereto by bolts 68 or the like. Arranged below and extending longitudinally of the beam 10 is 5 a conveyer or lifter 69, preferably in the form of an elongated plate, the same having its forward end connected with the lower end of the excavator, the upper surface of the conveyer being flush with the corresponding surface of the lower end of the excavator, as shown. The conveyer or lifter is 10 longitudinally inclined and its upper end is rigidly attached to the upper portion of the vertical arm of the beam extension 27, as shown. The conveyer is also laterally inclined, to discharge the dirt away from the land-side, or in other words, the land-side edge of the conveyer is arranged above its mold-board edge. 15 Arranged upon opposite sides of the conveyer 69 are independently vertically movable mold-boards 70 and 71, adapted to move the dirt from proximity to the ditch, when passing off of the conveyer. In the patent the mold-board and the land-side as they are termed therein were rigidly connected whereby they move together. I have found it advantageous to have two mold-boards extending in opposite directions and being 20 independently vertically movable. As a rule, very little dirt falls upon the mold board 71, whereby it need not be vertically adjusted as frequently as the mold-board 70, whereby it is advantageous that these members should move independently of each other, as above stated. The mold-boards 70 and 71 (see Fig. 7), are provided with apertured ears or knuckles 72, mounted to slide upon guide rods 73, attached to the lower 25 side of the conveyer 69 in spaced relation thereto. These elements are further provided with guide arms 74, rigidly attached thereto, the inner ends of which are apertured to slidably receive auxiliary guide rods 75, the forward ends of which extend into apertured ears 76 of a bracket 77, which is rigidly attached to the lower side of the conveyer 69. The rear ends of the auxiliary guide rods 75 are rigidly attached to the 30 lower end of the vertical arm of the L-shaped beam extension 27, by means of bolts 78 or the like. The mold-board 70 is preferably provided with a rearwardly extending arm 79, to which is attached a retractile coil spring 80, connected with one of the diagonal braces 46. The function of this spring is to aid in returning the mold-board 70 to the lower position, the same tending to gravitate to such position. I have found 35 it unnecessary to provide the mold-board 71 with a spring for returning the same to the lower position, as the same operates satisfactorily by gravity, while it is to be understood that a spring may be employed if desired. 40

The operation of the apparatus is as follows: The operator is positioned upon the seat 35, and may conveniently turn the hand wheel 63 to raise and lower the forward end of the beam 10, while the machine is being 45 drawn forwardly by the horses or other means. The excavator or cutter 64 engages with the ground, cutting the ditch or trench. The dirt travels rearwardly upon the conveyer or lifter 69, and the greater portion of the dirt is deflected to the right upon the mold-board 70, which removes the same from proximity to the cutter and the ditch. Some of the dirt however falls from the upper opposite edge of the conveyer and is removed from proximity to the same by the mold-board 71. The mold-boards are capable of moving vertically with respect to the conveyer and are self-adjusting, the same being further elevated as the depth of 50 the trench or ditch increases. The crank-axle 36 and wheels 43 prevent the lateral tilting of the body portion of the machine, the same however allowing the rear end of the beam to move downwardly, with respect to the wheels 43, as the depth of the ditch increases, while the supporting wheels 20 and 21 carry substantially all the weight of the machine. 55

It is obvious that the ditch may be dug in 60 various depths, depending upon the number of times that the machine is driven over or through the same.

It is to be understood that the form of my invention herewith shown and described is 65 to be taken as a preferred example of the same, and that various changes in the shape, size, and arrangement of parts may be resorted to without departing from the spirit of the invention or the scope of the subjoined claims. 70

Having thus described my invention, I claim:—

1. In a machine for digging ditches or trenches; a longitudinal support; supporting wheels connected with the support near its ends; a ground treating implement connected with the support between the supporting wheels and depending from the support; and self-adjusting means for preventing the lateral tilting of the longitudinal support, comprising a crank-axle extending transversely of the longitudinal support and permanently freely pivotally connected therewith and having cranks arranged upon the opposite sides of the longitudinal support, balancing wheels carried by the cranks, and yielding means to oppose the turning movement of the crank-axle in one direction. 80

2. In a machine for digging ditches or trenches; a longitudinal support; a ground treating implement connected with the support; supporting wheels connected with the ends of the longitudinal support; means for 85

- raising and lowering the forward end of the longitudinal support with relation to the adjacent supporting wheel embodying a manually moved element arranged near the rear end of the longitudinal support; an operator's seat carried by the rear end of the longitudinal support and disposed near the manually moved element; and self-adjusting means to prevent lateral tilting of the longitudinal support, comprising a transverse crank-axle permanently freely pivotally connected with the rear end of the longitudinal support and having cranks disposed upon the opposite sides of the longitudinal support, balancing wheels carried by the cranks, an arm rigidly connected with the crank axle, and a spring connected with the arm and a portion of the longitudinal support.
3. In a machine for digging ditches or trenches; a longitudinal support; supporting wheels connected with the longitudinal support near its ends and normally arranged

in approximately the longitudinal axis of such support; cranks permanently freely 25 pivotally connected with the support and disposed upon opposite sides thereof; balancing wheels carried by the cranks; yielding means to oppose the movement of the cranks in one direction; and a ground treating implement connected with the longitudinal support.

4. In a machine for digging ditches or trenches, a wheeled support, ditch digging means carried thereby, a conveyer arranged 35 rearwardly of the ditch digging means to receive dirt therefrom, and laterally extending independently vertically movable mold boards arranged near and upon opposite sides of the conveyer.

In testimony whereof I affix my signature in presence of two witnesses,

EDWARD JESCHKE.
